UNITED STATES PATENT OFFICE.

LUIS B. HOCHSTEIN, OF ENDICOTT, NEW YORK.

CLASP.

1,345,183.

Specification of Letters Patent.

Patented June 29, 1920.

Application filed December 18, 1919. Serial No. 345,733.

To all whom it may concern:

Be it known that I, LUIS B. HOCHSTEIN, a citizen of the United States, and a resident of Endicott, in the county of Broome 5 and State of New York, have invented a new and Improved Clasp, of which the following is a full, clear, and exact description.

The present invention relates to new and 10 useful improvements in clasps and it pertains more particularly to clasps of the pivoted type.

The primary object of the present invention is to provide a device of this character 15 especially adapted for retaining the open ends of a box or pasteboard carton in closed relation.

A further object of the invention is to provide a device of this character which 20 may be entirely removed when in its inoperative position.

A still further object of the invention is to provide a device of this character which will lie flat to the box when in its operative 25 position.

With the above and other objects in view, reference is had to the accompanying drawings, in which—

Figure 1 is a front elevation of the side 30 of a carton partly broken away and showing the device in its operative position in full lines and in its inoperative position in dotted lines;

Fig. 2 is a sectional view taken on the line 35 2—2 of Fig. 1;

Fig. 3 is a sectional view taken on the line 3—3 of Fig. 1, and showing a portion of the fastener broken away;

Fig. 4 is a disassembled perspective view 40 of the device;

Fig. 5 is a perspective view of a modified form of the bail member.

Referring more particularly to the drawings, the device comprises two substantially 45 U-shaped members A and B, which are adapted to be pivotally secured together to form the clasp. The U-shaped member A is preferably rectangular in conformation and it consists of a base portion 5, from which 50 project two legs 6. The base portion 5 and the leg portions 6 are bent at their point of juncture to form a loop 7. Each of the legs 6 has its free end terminating in a right-angular portion 8, the other end of which is 55 in turn bent at right angles to form inwardly disposed hooked extremities 9.

The U-shaped member B is preferably curved in conformation and is formed from resilient wire. This curved U-shaped member B is provided on the free end of each of its legs with a looped portion 10, which looped portions 10 are adapted to engage the looped portions 7 of the U-shaped member A to pivotally secure the member B to the member A.

The reference characters 20 and 21 designate the meeting edges or flaps of a cardboard box or carton, and the member 20 is provided with two spaced openings 22, the member 21 being provided with two spaced 70 openings 23.

In operation the two members A and B are pivotally secured together as heretofore described, and the legs 6 of the U-shaped member A are inserted through the openings 75 23 in the flap 21 of the box. The other flap is now positioned so that its openings 22 will receive the right-angular ends 8 of the U-shaped member A with the right-angular extremities 9 projecting therethrough. With 80 the parts in this position, the U-shaped member B is swung down to the point where it engages beneath the right-angular hooked extremities 9 of the right-angular portions 8 of the legs 6 of the U-shaped member A. 85

When it is desired to remove the device, the legs of the U-shaped member B are grasped and compressed which contracts the width of the U-shaped member B to such an extent as to permit of its legs being withdrawn from beneath the right-angular extremities 9 of the legs 6, as shown by dotted lines in Fig. 1. With the parts in this position, the curved U-shaped member B is capable of swinging about its pivotal point to 95 release the flap 20.

In the modified form shown in Fig. 5, the bail member B is provided with bent portions D which are adapted to receive the inwardly disposed hooked extremities 9.

In some instances, it may be desired to use the device for closing the open portions of articles made of flexible material, such as canvas, burlap, and the like, and in such cases the legs of the curved U-shaped member B are provided with depressed portions as above mentioned, at that point throughout their length where they are engaged by the right-angular extremities 9 of the U-shaped member A.

I claim—

1. A device of the character described

comprising a plurality of **U**-shaped body portions adapted to be pivotally secured together, one of said **U**-shaped body portions being pivotally secured at its base to the free ends of the leg members of the other of said **U**-shaped body portions, and means carried by the ends of the legs of the **U**-shaped body portion pivotally secured at its base for engagement with the legs of the other **U**-shaped body portion near its ends to secure the device in operative position.

2. A device of the character described comprising a pair of **U**-shaped body mem-

bers adapted to be pivotally secured together, one of which is provided with a plurality of loops at its base and adapted for engagement with loops provided at the free ends of the legs of the other **U**-shaped body member for pivotally securing the two together, and means formed on the free ends of each leg of the first-mentioned **U**-shaped member for engagement with the legs of the other **U**-shaped member to secure the device in operative position.

LUIS B. HOCHSTEIN.
